UNITED STATES PATENT OFFICE

130,952

DESIGN FOR A NEON TUBE INSULATOR HOUSING

Samuel C. Miller, New York, N. Y.

Application February 20, 1941, Serial No. 99,133

Term of patent 14 years

To all whom it may concern:

Be it known that I, Samuel C. Miller, a citizen of the United States and a resident of New York, in the county of New York and State of New York, have invented a new, original, and ornamental Design for a Neon Tube Insulator Housing, of which the following is a specification, reference being had to the accompanying drawing, forming a part thereof.

Figure 1 is a perspective view of a neon tube insulator housing showing my new design;

Figure 2 is a top plan view thereof;
Figure 3 is a bottom plan view thereof;
Figure 4 is a side view thereof, slightly diminished in size;
Figure 5 is an end elevational view thereof.
I claim:

The ornamental design for a neon tube insulator housing, as shown.

SAMUEL C. MILLER.
